SPORTS CLOCK

Robert Steeneck, New York, and Robert F. Dirkes, Jamaica, N. Y., assignors to The Western Union Telegraph Company, New York, N. Y., a corporation of New York

Application May 29, 1934, Serial No. 728,154

11 Claims. (Cl. 161—17)

This invention relates to clocks or other timing devices primarily adapted to timing of games or other events, such as football, basketball, lacrosse, and the like.

5 The general object of this invention is to provide a large dial clock which may be operated by an official to time the game and to be set up in connection with the game score board or set up separately in a position in which it 10 may be viewed by the audience or those attending the event. Another object is to provide multiple units of this clock when it is necessary, in order to permit the entire audience to observe the time progress of the game.

15 In the majority of games or sports events which command wide popularity, time is of the essence in determining the course of the game or event. However, the methods mainly employed for timing such events are archaic and substantially no improvement has been made in recent 20 years in the methods of keeping time in such events. Usually the time is kept by an official charged with that duty from a small stop watch or like device of which he has full charge and 25 which is not visible to anyone except himself. However, the audience or spectators of the game are quite as interested in the time progress of the event as in the skill displayed by the participants. Where clocks or timing devices constructed according to this invention have been 30 installed a noticeable increase in interest in the game on the part of the spectators is quite evident.

In addition, often times the accuracy of timing 35 an event is brought into dispute and the integrity of the official timekeeper is sometimes doubted. This is less likely to occur, however, when the clock or other timing device operated by or under the control of the official timekeeper 40 is displayed in full public view since it is easier to detect actual timing mistakes when they are made.

It is a further object of this invention, therefore, to provide a sports timing mechanism, 45 which may be displayed in full public view, and which will perform all of the functions ordinarily performed upon the timing instrument commonly employed by the timekeeper.

Another object is to provide means to control 50 such a timing device from some remote central point or points, such control to embody means for starting and stopping the clock, as the plays of the game progress, and also for setting the clock to a new position when necessary during 55 the progress of the game.

Another object is to provide a clock employing a large dial, having correspondingly large hands, one of which makes a complete revolution in one minute, as with the ordinary clock or stopwatch and another of which makes a revolution 5 or a predetermined portion thereof during the time allotted for each game period, such as the quarters in the case of football.

A further object is to automatically stop the time clock or clocks at the end of each play 10 period and to automatically operate a signal indicating of the termination of the time period.

A still further object is to provide means for operating several clock units in unison from a single control point. 15

Still another object is to provide means to synchronize periodically, during the progress of the game, the several clock units.

A still further object is to provide a portable control means, which may be employed by a 20 sideline referee for instance in timing a game of football, for operating the timing mechanism as he follows the progress of the teams over the field.

Still another object is to provide a signal to 25 indicate the exact moment when the official starts and stops the clock.

These and other objects of this invention will be apparent from the following description and claims taken in connection with the accompanying drawings, in which— 30

Fig. 1 shows a plan view partly in section of the operating mechanism or movement of the timing device;

Fig. 2 is an end view taken along the line 35 2—2 of Fig. 1, omitting the drive motor and the shaft geared thereto;

Fig. 3 is a sectional view on the line 3—3 of Fig. 1;

Fig. 4 is a diagrammatic view of the wiring for 40 operating two clock units together; and

Fig. 5 is a view in elevation of the dial.

The clock units, according to this invention, are duplicates of each other, substantially identical in form, and any desired number may be 45 operated in unison substantially as described hereinafter.

Each unit in its preferred form employs a dial 50 such as illustrated in Fig. 5. The particular dial illustrated is intended for use in connection with games employing 15 minute periods, such as football. In its preferred form the dial is divided into 15 time periods and is enumerated in reverse order from the progress of the clock hand. In connection with the dial, preferably 55

two hands are employed in indicating the time. The small or seconds hand 11 is arranged to rotate clockwise, making a complete revolution in one minute. The large hand 12 is arranged to rotate in a clockwise direction, making one complete revolution for each of the time periods in which the game is divided. Thus for football the hand makes a complete revolution in 15 minutes.

10 It will be observed in following the dial from zero in a clockwise direction that the numerals on the dial are respectively 12, 9, 6 and 3. The purpose of this is to cause the clock to indicate the time in minutes remaining in each time period, or in other words, the number of "minutes to go". Thus when the hand 12 reaches the first numeral on the dial three minutes of the game period will have elapsed and there will be twelve minutes remaining, which is the indication on the dial. It should be borne in mind, however, that the clock may be employed with equal advantage to measure the game period in time elapsed as in ordinary clock measurement or time indications.

25 In addition to the above features, according to this invention, a signal light 13 is displayed upon the dial. These lights are preferably arranged to be lighted when the clock is in operation or is measuring time and extinguished when the clock is stopped. The lighting and extinguishing of the lights, therefore indicates to the observers the exact time when the clock is started and stopped by the official operating the same. By this means the spectators are enabled to compare the operation of the clock with the observed actual length of each play in the game. This increases the incentive for the timekeeper to be exact in his following of the plays of the game. It will also largely settle controversies involving the question of whether the time recorded corresponded to the actual play. As will be described hereinafter automatic means for stopping the clock at the end of a game period will largely eliminate controversies in connection with football and similar games, as to whether the final play was completed within the game period.

50 The operating mechanism for a clock unit as shown in Figs. 1, 2 and 3 consists of a constant speed motor 15, which may be either a synchronous motor driven from a well regulated alternating current supply or a governed motor held at a substantially constant speed, such as a motor employing a very sensitive governor or a tuning fork control. This motor is geared to a shaft 55 16. In the particular embodiment shown the ratio of the drive is preferably such that the speed of the shaft 16 will be 300 revolutions per minute. It is to be understood, however, that any other assigned speed may be employed. The shaft 16 is coupled through a crown clutch, embodying a driving member 17 and a driven member 18, to a gear box 19. The speed is reduced through this from 300 R. P. M. on the high speed shaft to 1 R. P. M. on the slow speed shaft 21. This shaft extends through a net work of mechanism to the front of the clock dial 10 to carry the seconds hand 11.

70 The clutch members 17 and 18 are normally held in engagement through the action of spring 22 when the clutch magnet 23 is energized. Upon de-energizing of clutch magnet 23, the rounded portion of its armature 24 cams-out the driven clutch member 18, thus disengaging it from the driving member 17 connected to the counter-shaft 16. A jockey roller 25 is provided to hold

driven clutch member 18 in its cammed-out position until magnet 23 is again energized. This method of clutching stops the clock in steps of fifths of a second. Magnet 23 is energized and de-energized under the influence of a time keeper in accordance with the rules of the game. 5

The minutes hand 12 is driven from the seconds hand shaft 21 through a planetary gear system. The planet wheel mounting 26 is directly connected to shaft 21 and carries planet wheels 27 and 28 which are directly connected to each other by a shaft 29 free to rotate in the bearing furnished by the mounting 26. Planet wheels 28 and 29 mesh respectively with two internal gears 31 and 32. Internal gear 31 is normally held from rotation by armature 33 of magnet 34, thus forming the sun wheel of the planetary system. Internal gear 32 is the driven wheel and is solidly connected to the minutes hand 12 through a sleeve 35 bearing on shaft 21. Due to the fact that planet wheels 27 and 28 have a different number of teeth, a relative motion is imparted to gear 32 with respect to gear 31, as the planet wheels rotate within these two internal gears. Planet wheel 27 has fifteen teeth 25 and planet wheel 28 has fourteen teeth in the particular embodiment shown. Internal gears 31 and 32 both have seventy-five teeth, thus driving the minutes hand 12 at one-fifteenth the speed of the seconds hand when sun wheel 31 30 is held from rotation, as will be explained hereinafter. Every revolution of planet wheel 27 with respect to sun wheel 31 causes internal driven gear 32 to move one tooth with respect to sun wheel 31. Thus, when the shaft 21 makes 35 one revolution carrying the planet wheel mounting 26, therewith, the driven gear 32 will move five teeth with respect to the sun wheel 31 or one-fifteenth of a revolution.

40 Sun wheel 31 has fourteen notches cut in its periphery which engage with the armature 33 of magnet 34. A friction plate 36 pushed against the sun wheel 31 by a spring 30 tends to rotate the wheel 31 as a unit with shaft 21. Armature 33, however, prevents this rotation. Upon the 45 release of the armature 33, however, internal sun wheel 31 is free to rotate with shaft 21 through the friction drive of disk 36. Thus, the planetary unit acts as a solid coupling and the minutes hand 12 rotates at the same speed as the 50 seconds hand 11. Releasing the sun wheel 31 for one notch has the equivalent effect of moving the minutes hand 12 through an arc corresponding to one minute. Thus, it is possible to adjust the initial position of the minutes hand to correspond to a shortening of the playing time of a period from fifteen to any other time, in minutes. This is highly desirable in preseasonal games or in other games where weather or other conditions so dictate. This may be accomplished 55 by releasing armature 33 for a number of notches corresponding to the number of minutes it is desired to cut from the normal playing time. This may be done during the progress of the game without taking any playing time from the game 60 for the purpose of setting the clock. This also provides a convenient means for quickly setting the clock to zero before the beginning of the game should for some reason the hands be in some other position at that time. 65

70 Two sets of contacts 37 and 38 are provided for automatically stopping the clock when both hands reach zero at the end of a period. The minutes hand contact 38 is closed by a projection 39 attached to the minutes hand gear 32. 75

The seconds hand contacts 37 are closed instantaneously by the depressed portion of the cam 41 when the seconds hand reaches zero. When both contacts are closed a relay is energized, de-energizing start magnet 23 which in turn disengages clutch members 17 and 18, thus stopping the clock mechanism at zero.

In some football stadiums, one clock would be sufficient for use in timing the games. However, the construction of most stadiums makes the use of two clocks necessary in order that all spectators may conveniently see at least one time piece. For our description of the control circuits we have elected to show the apparatus necessary for controlling two clocks. In Fig. 4 we have shown diagrammatically two clocks A and B. While the clocks A and B are illustrated as having different control arrangements, it will be obvious from the following description that the controls may be exactly the same in both clocks.

At the start of a game it is necessary to start both clocks in motion. The timekeeper accomplishes this by closing switch 42 in the time control switch set 43. Closing switch 42 applies a ground through the tongues and back contacts of relays 44-A and 44-B and through the back contacts and tongues of keys 45-A and 45-B to start magnets 23-A and 23-B. The other terminals of start magnets 23-A and 23-B are connected to battery. Thus start magnets 23-A and 23-B are energized, starting clocks A and B by engaging their clutch members 17, 18 as has been previously described. Switch 42, in addition, grounds relay 46 which at present performs no function and the purpose of which will be explained later in this description.

When the rules of the game require that the clocks shall be stopped, the operator opens switch 42, thereby removing the ground from start magnets 23-A and 23-B and thus stopping clocks A and B by disengaging their clutch members 17, 18. The clutch mechanisms of both clocks A and B are designed to stop the units at the nearest fifth of a second interval following the opening of switch 42, this being the rotation time of the shaft 16, as has been previously described. Thus, if either clock be slightly out of phase with the other, both units will be brought into a synchronous position at this stopping point. This eliminates the chances of accumulative error due to slight differences in speed of clutching and declutching the units.

Start magnet 23-A has operating signal relay 47 connected in series with its circuit. Operating signal relay 47, when energized, applies a ground through its armature 48 and conductor 49 to signal lamps 13 and 14 in the clock dial 10. Operating signal relay 47, being in the start magnet circuit, energizes every time switch 42 is closed, thus lighting signal lights 13 and 14, giving a visual signal that the clocks are in operation. It will be noted that these lights are controlled from the A clock circuit. Individual controls simultaneously operated may be provided for each clock if desired.

Keys 45-A and 45-B are provided for controlling clocks A and B independent of switch 42. This may be of advantage in setting the clocks to zero before the start of the game. These keys 70 are not intended to form a part of the timing system but are simply a convenience in operating one clock without operating the other, as may sometimes be necessary.

At the end of the period both hands 12-A and 11-A (not shown) approach zero. As min-

utes hand 12-A approaches zero, contacts 38-A are closed by the cam 39-A on the gear 32-A and apply a ground to one of the contacts of 37-A which remain open until seconds hand 11-A reaches zero. When hand 11-A reaches 5 zero, contacts 37-A close by falling in the depression of cam 41-A and transfer the ground through the tongue and back contact of relay 51-A to the winding of relay 44-A which then energizes and opens the circuit through start 10 magnet 23-A. Start magnet 23-A thus deenergizes and the mechanism of clock A is stopped as heretofore described. At the same time operating signal relay 47 is deenergized and signal lights 13 and 14 are extinguished. Relay 44-A 15 upon being energized grounds the signal horn 52 which operates, thus giving an audible signal that the end of the period has been reached. The signal continues until the ground from the horn is released by opening of switch 42. A circuit similar to that described for clock A is also provided for clock B, except in that no duplicate signal apparatus is provided. The circuit for clock B is independent of that for clock A, thus should clock B be slightly out of phase with clock 25 A synchronism will be restored at the zero point due to the fact that both clocks stop independent of each other.

With the clocks stopped automatically at zero, it is obviously necessary to provide some circuit 30 for again starting these clocks from this zero position. For that purpose, zero reset relay 46 is provided. As explained before this relay is energized when switch 42 is closed and deenergized when switch 42 is opened. In its deenergized position relay 46 connects contact 37-A to zero start relays 51-A and 51-B. During normal operation this has no effect upon relays 51-A and 51-B since either contacts 37-A or 38-A are open. However, at the end of the period when 40 clocks A and B stop automatically (switch 42 being closed and zero reset relay 46 being energized), a ground is placed upon the back contact of relay 46 through the closure of contacts 37-A and 38-A as has been previously described. 45 Thus, upon opening switch 42, relay 46 is deenergized and the ground transferred to relays 51-A and 51-B, thus energizing them. Relays 51-A and 51-B, upon being energized, open the circuits through zero stop relays 44-A and 44-B, 50 thus deenergizing them. Relays 44-A and 44-B in their deenergized position again restore continuity to the start magnet circuits 23-A and 23-B, thus placing the clocks A and B in a position to again start. The ground from contacts 55 37-A, when relay 51-A is energized, is carried through the tongue of relay 51-A to the front contact thereof, thus maintaining relays 51-A and 51-B energized as long as contacts 37-A and 38-A are closed. When contacts 37-A 60 are again open, relays 51-A and 51-B will be deenergized and since the ground holding circuit is broken, there will be no danger of energizing relay 44-A until the hands of the clock have again made their complete circuit. It should be noted, 65 however, that the contacts 37-A should open later than contacts 37-B, for should they open earlier the ground applied through contacts 37-B would in turn energize relay 44-B, thus stopping clock B. This overlap is easily accomplished by 70 making the depression in cam 41-A considerably longer than in cam 41-B.

Push button 53 is provided in time control switch set 43 for stepping the minute hands 12-A and 12-B around in unison with the seconds 75

hands 11—A and 11—B. This may be necessary before the beginning of the game in order to quickly set both clocks to zero or when it is desired to cut any desired number of minutes from the playing time of a period due to pre-seasonal games or other conditions. Depressing button 53 applies a ground through the back contacts and tongues of keys 54—A and 54—B to magnets 34—A and 34—B which are thus energized. Magnets 34—A and 34—B when energized release sun wheels 31—A and 31—B and allow hands 11—A and 12—A and 11—B and 12—B to revolve in unison. When it is desired to shorten the period, push button 53 may be depressed while clocks A and B are running, held for about a second, and then released. This will allow the sun wheels to revolve one notch and will shorten the playing time one minute. The operation is repeated for the desired number of minutes to be cut from the period. Keys 54—A and 54—B are provided for applying this function to each clock independently should it be so desired.

Since the clocks are controlled by the single switch assembly 43, connected to the control mechanism through flexible conductors, it is evident that a considerable latitude of movement is provided for the timekeeper, thus enabling him to accompany the progress of the players along the field. It is obvious, of course, that various changes may be made in the details of construction of the timekeeping mechanism and that while it has been shown particularly for the timing of football games, it may, either in the form shown or by suitable modification be employed for timing other games or events.

What is claimed is:

1. In a time clock having a pair of hands with means for normally rotating the hands at relatively different speeds for time measurement, means for changing the normal speed of rotation of one of said hands for setting the same during rotation of the other of said hands at normal time measuring speed and automatic means for restoring the speed of rotation of said hand to normal at any one of a plurality of predetermined positions in its rotation with relation to said hand rotating at normal time measuring speed.

2. In a time clock having a pair of indicators with means for normally rotating the indicators at relatively different speeds for time measurement, frictionally driven means for changing the normal speed of one of said indicators for setting the same, control means for said frictionally driven means designed to return said last named indicator to its normal speed of rotation at one of a plurality of definite positions in its movement with relation to the other indicator whereby said indicators will be in correct relative positions after a change in the normal speed of one.

3. In a time clock for measuring and indicating the progress and termination of a predetermined time period, a time indicator and a motor for driving the same, means for starting the time indicator from a normal starting position, means for stopping the indicator when it reaches a predetermined stopping position, and means acting while the motor is in operation for advancing the time indicator in excess of its normal rate of travel for shortening the period which would normally elapse if said indicator traveled at its normal rate from its starting to its stopping position and having means provided for automatically stopping the excess travel of the indicator

when its period has been shortened a predetermined amount.

4. The combination with a timing clock movement embodying time measuring and indicating means, said means including a pair of indicators, start-stop means for arbitrarily starting and stopping said time measuring means, means operable to advance said indicators together at the same speed through a predetermined angular distance at any time during a time measuring operation, and control means operatively connected with the clock movement embodying means for controlling both the start-stop means and the means to advance the time measuring means.

5. In a clock for timing athletic contests, a pair of rotary shafts, a motor and means to drive one of said shafts from said motor, an indicator hand on each of said shafts, a planetary gear train having a fifteen to one gear ratio driven from said motor driven shaft and operatively connected to drive the other of said shafts at a reduced speed, a friction member secured to said motor driven shaft in frictional engagement with a gear element of said planetary gear train, a series of fourteen equally spaced notches on said gear element and releasable means for engaging said notches to arrest progression of said gear element under the influence of said friction member.

6. A time clock for measuring and summatting increments of a predetermined total time separated by intervals not to be measured and of the type which embodies a clock with one or more summation indicators and a motor for driving the indicators, said clock embodying means including a normally open electrical circuit for automatically stopping the indicators by closing said circuit when the summation reaches a predetermined total and means including a manually operable switch for opening said circuit to permit advancing the clock from its stop position by said manually operable switch after it has been automatically stopped.

7. In a time clock movement embodying a time shaft and a time indicator rotatable therewith at a predetermined speed, a second time shaft and a second indicator rotatable therewith at a relatively slower speed, means for rotating the second named shaft at the speed of said first named shaft operable at any relative position of said indicators when setting said second named shaft to a new position, and means for restoring said second named shaft to the normal speed thereof after rotating through any one of a plurality of predetermined angular distances.

8. A timing system for measuring cumulative increments of a predetermined total time and of the type which embodies a clock having a timing indicator and a motor for driving said indicator, said system having means including a normally open electrical circuit for automatically arresting forward movement of the indicator upon closing of said circuit at a predetermined time, a second circuit, a manually operable switch in said second circuit, a perceptible signal, means to cause operation of said signal upon closing of said first circuit, and means for opening said first named circuit when said switch is opened, the opening of said switch causing said signal to cease operation.

9. In a time clock, a constantly running motor, a time indicator, means to drive said time indicator from said motor including a clutch, said clutch comprising a driving and a movable driven member, the latter serving to drive said indi-

cator, interlocking elements on said driving and driven members to provide a positive driving connection therebetween, a stop projection on said driven member having a cam surface, and a member movable into the path of said projection 5 to cooperate with said cam surface thereby disengaging said clutch members and arresting forward motion of said driven member.

10. In a clock for timing athletic contests, timing means including a pair of indicators, power means and means to drive one of said indicators from said power means, a planetary gear train driven from said power driven indicator and operatively connected to drive the other of said indicators at a reduced speed, a clutch member 15 driven from said power means and cooperating with a gear element of said planetary gear train to drive the same at times, a series of fourteen

equally spaced stop means on said gear element and releasable means for engaging said stop means to arrest progression of said gear element under the influence of said clutch member.

11. In a time clock movement embodying a 5 time indicator movable at a predetermined speed, a second time indicator movable at a relatively slower speed, means for moving the second named indicator at the speed of the first named indicator operable at any relative position of said indicators 10 when setting said second named indicator to a new position, and means for restoring said second named indicator to the normal speed thereof after moving through any one of a plurality of predetermined distances. 15
